UNITED STATES PATENT OFFICE.

SAMUEL G. MUSSER, OF LOS ANGELES, CALIFORNIA.

CENTRIFUGAL AMALGAMATOR.

1,317,986.

Specification of Letters Patent.

Patented Oct. 7, 1919.

Application filed July 19, 1917, Serial No. 181,474. Renewed November 4, 1918. Serial No. 261,161.

To all whom it may concern:

Be it known that I, SAMUEL G. MUSSER, a citizen of the United States, residing at Los Angeles, in the county of Los Angeles, 5 and State of California, have invented a new and useful Centrifugal Amalgamator, of which the following is a specification.

This invention relates to amalgamators of the type designed to utilize centrifugal action to force metalliferous ores into contact with a body of mercury, and an object of 10 the invention is to produce a machine of this character which will effect maximum amalgamation of the metal passing through 15 the device.

Another object is to minimize the loss of mercury used in the machine.

Another object is to minimize internal pressures so as to reduce the liability to 20 leakage of the mercury through the various joints between the different parts of the apparatus.

Another object is to facilitate the gaining of access to the interior of the machine.

Other objects and advantages will appear in the subjoined detail description.

The accompanying drawings illustrate the invention:

Figure 1 is an elevation from the discharge side partly in vertical mid section of a centrifugal amalgamator built in accordance with this invention.

Fig. 2 is a plan section on line indicated by x^2-x^2 , Fig. 1.

Fig. 3 is a plan section on the irregular line indicated by x^3-x^3 , Fig. 1.

Fig. 4 is a sectional detail of a portion of the shell showing the discharge pipe in discharge position.

There is provided a base member 1 which may be chambered at 2, the intermediate portion of said member having a helical passage 3, and there being a discharge opening at 4 at the lower end of the passage.

Mounted on the base member 1 is a standard comprising legs 5 fastened by cap screws 6 or equivalents to the top of the base member. The upper ends of the legs 5 are joined together to form a boss 7, and passing through said boss is a tubular vertical intake member 8. The tubular intake member 8 is in the form of a stationary hollow stud shaft provided with an enlarged bearing portion 9 to journal thereon a rotative sleeve 10. Any

suitable packing is provided adjacent the stationary bearing portion 9 and the sleeve 10 to prevent or minimize leakage of ma-

terial between said members. In this instance the packing is formed of one or more cups 11 of leather or other suitable material 60 alternatively arranged with spacing collars 12, said cups and collars being retained in position by a shoulder 13 terminating the upper end of the bearing portion 9 and by a plug 14 fastened by a key 15 or equivalent 65 to the tubular member 8.

The sleeve 10 is fastened by cap screws 16 or equivalent to a hollow cone-shaped member 17 which in turn is fastened by cap screws 18 or equivalents to the upper end of 70 a shell 19 which is provided with an annular passage extending in an outer portion 20 from near the upper end of the shell to near the lower end thereof, thence downwardly and inwardly in an inclined portion 21, 75 thence upwardly and inwardly in a curved portion 22, thence upwardly in an intermediate portion 23. The upper end of the passage portion 20 terminates in a shoulder 24 and the upper end of the inclined portion 80 21 terminates in an annular shoulder 25 and when the machine is in operation the mercury, not shown, occupies that portion 20 of the passage extending between the shoulders 24 and 25. The portion 20 of the passage is formed between the outer wall 26 of the shell and an intermediate wall 27 of said shell, and the passage portions 22, 23 are formed between an intermediate wall 28 and an intermediate wall 29. The intermediate 90 walls 28 and 29 need not be, and preferably are not, as long as the intermediate wall 27. The intermediate wall 27 extends upwardly and inwardly in a curved portion 30 which is spaced from the conical member 17 to 95 form an upward extension of the passage portion 20. The curved portion 30 joins a cover portion 31 which is fastened by cap screws 32 or equivalents to a collar 33 which is mounted on the upper portion of and rotates with a vertical central shaft 34.

Extending downward from the collar 33 is a tubular member 35 forming an inner wall of the shell 19 provided with an annular lip 36 which meets the upper portion of the 105 intermediate wall 28 to form the joint 37. The lower portion of the tubular member 35 forms the inner wall of a passage portion 38, the outer wall of said passage portion being formed by the inner wall 29. From the foregoing it is clear that there is an annular 110 passage leading downwardly from the intake member 8 to near the bottom of the shell 19, thence upwardly and inwardly and

thence downwardly. It is also clear that the walls 27, 28 overlap the wall 29 and are inserted between the walls 26, 29. The passage portion 38 terminates at its lower end in 5 downwardly and outwardly peripherally-discharging nozzles 39 which are gradually reduced outwardly and which are arranged to discharge in a direction opposite to the direction of rotation so that centrifugal action 10 will to a greater or less degree tend to cause flow of the ore through the machine. Under some conditions it may be advisable to extend the nozzles 39 to increase the centrifugal discharging action and for that purpose 15 nozzle extensions 40 may be provided as shown in the drawings, said nozzle extensions being fastened by cap screws 41 or equivalent to the outer wall of the shell 19 so that the bores of the nozzles and nozzle extensions 20 align with one another. It is understood that this machine will function without the nozzle extensions 40 if so desired.

The passage portion 20 is of slightly less diameter at its lower end than at its upper 25 end and the passage portion 23 is of slightly less diameter at its upper end than at its lower end. Likewise the passage portion 38 is of less diameter at its upper end than at its lower end. This is for maximizing conservation 30 of the mercury and facilitating the flow of the metalliferous ore through the passage.

The lower end of the shaft 34 is supported in a step-bearing 41 which is fastened by cap 35 screws 42 or equivalent to the base member 1. The shaft 34 is provided with a pulley 43 just above the step-bearing 41, and the upper portion of the shaft is journaled just beneath the collar 33 at 44 in a tubular upwardly 40 extending portion 45 of the base, there being a clearance between said tubular member and the tubular member 35.

At the lowest point in the passage portion 22 is an inwardly reduced clean-out port or 45 ports 46 in which fits a tapered plug or plugs 47 having a head or heads 48 suitable for turning by a wrench, not shown. The plug is provided with an inwardly extending internally threaded sleeve 49 adapted to engage 50 the externally screw-threaded reduced portion 50 of a nipple which also comprises an enlarged externally screw-threaded portion 51. The bore of the nipple forms the outer portion of the port 46.

55 In practice, the desired amount of mercury will be run into the passage portion 20 of the machine and power will be applied to the pulley 43 to rotate the collar 33 and the parts connected with said collar, thus causing 60 the mercury, not shown, to form an annular body in the passage portion 20 between the shoulders 24, 25. The crushed metalliferous ore to be amalgamated will be introduced under suitable pressure through 65 the intake member 8 into the passage portion

20 and centrifugal action will cause the heavier particles, which of course are the metal particles in the ore, to occupy the peripheral portion of the tubular column of downwardly moving ore. These metal particles will be forced against the inner face of the mercury body and into said body in a manner well understood in the art pertaining to centrifugal amalgamation and amalgamation of the metal particles will take place, 70 and the remaining material or tailings will flow through the passage portions 22, 23 and 38 to the nozzles 39 and will be forced outwardly from said nozzles into the helical passage 3 of the base 1. The force of discharge of the material from the nozzles 39 is sufficient to cause the material to flow from the helical passage 3 through the discharge opening 4.

When it becomes necessary or desirable to remove the amalgam from the machine, operation of the machine will be stopped, whereupon the amalgam will flow into the lower portions of the passage portions 20 and 22. Pipes indicated in broken lines at a 80 Fig. 1, will be screw-threaded onto the enlarged portion of the nipples 51, and a suitable wrench, not shown, will be inserted in the pipes to engage the heads 48 of the plugs. Turning of the wrench will unscrew the 90 plugs and the amalgam will flow through the ports 46 into the pipes a and thence into a suitable container, not shown, placed at the discharge ends of said pipes a.

It is noted that the centrifugal action aiding in the discharge of the tailings from the shell is of advantage for the reason that the lower end of the passage in the shell is thereby cleared of the tailings so that the pressure of the incoming ore will not cause 100 the particles of the ore to become too closely packed in the passage. It is readily seen that owing to the centrifugal action tending to keep clear the lower end of the passage the pressure required to force the ore 110 through the machine is less on a given character of ore than if the centrifugal discharging action were not provided for. By having less pressures, it is clear that leakage of the material past the packing cups 11 and 115 through the various joints of the shell is minimized and is, in fact, practically eliminated.

From the foregoing it is clear that the centrifugal action of the tailings in the discharge end of the shell passage is sufficient to prevent clogging of the passage even though the force of the ore feed at the feed end of the passage be insufficient of itself to cause the ore to flow through the machine at a desirable rate of speed. The advantage of this is that pressures inside of the shell may be minimized so as to minimize leakage past the packing 11 and through the joint of the various sections of 130

the shell, thus the centrifugal action of the hollow rotating column of ore is utilized to aid in moving the column of ore through and in contact with a hollow body of mercury.

I claim:

1. In a centrifugal amalgamator, the combination of a shell provided with a passage extending downwardly, thence upwardly, thence downwardly again, means to rotate the shell, and outlet nozzles at the lower end of the passage arranged to discharge in a direction opposite to the direction of rotation.
- 15 2. In a centrifugal amalgamator, the combination of a shell having an annular passage, means in the passage to retain mercury when the shell rotates, means to rotate the shell, and outlet nozzles for the passage arranged to discharge in a direction opposite to the direction of rotation.
- 25 3. In a centrifugal amalgamator, the combination of a shell having an annular passage, means in the passage to retain mercury when the shell rotates, means to rotate the shell, and outlet nozzles for the passage arranged to discharge in a direction opposite to the direction of rotation, said nozzles being reduced outwardly.
- 30 4. In a centrifugal amalgamator, the combination of a shell having an annular passage, means to rotate the shell, an inlet for the passage at the upper end of the shell, and nozzles at the periphery of the shell for the lower end of the passage, said nozzles being arranged to discharge in a direction opposite to the direction of rotation.
- 40 5. In a centrifugal amalgamator, the combination of a shell having an annular passage, a base member having a tubular extension projecting inside of the shell, a shaft journaled at the upper end of the tubular extension and fastened to the shell and rotatively mounted at the lower portion of the base, means to turn the shaft, a tubular intake member extending into the shell, and outwardly directed nozzles at the discharge end of the annular passage.
- 45 6. In a centrifugal amalgamator, the combination of a base having a helical discharge passage, a rotatively mounted shell having an annular passage, nozzles for the discharge end of the annular passage adjacent the upper end of the helical passage in the base, and means to rotate said shell.
- 55 7. In a centrifugal amalgamator, the combination of a base, a vertical shaft rotatively mounted in said base, a shell mounted to turn with the shaft and provided with an annular passage, said shell having an upwardly extending sleeve communicating with said passage, a standard mounted on the base, and a hollow intake member supported by the standard and extending downward into the sleeve.

8. In a centrifugal amalgamator, the combination of a base, a vertical shaft rotatively mounted in said base, a shell mounted to turn with the shaft and provided with an annular passage, said shell having an upwardly extending sleeve communicating with said passage, a standard mounted on the base, and a hollow stud shaft supported by the standard and journaling the sleeve.

9. In a centrifugal amalgamator, the combination of a base, a vertical shaft rotatively mounted in said base, a shell mounted to turn with the shaft and provided with an annular passage, said shell having an upwardly extending sleeve communicating with said passage, a standard mounted on the base, a hollow stud shaft supported by the standard and journaling the sleeve, and packing between the sleeve and stud shaft.

10. In a centrifugal amalgamator, the combination of a shell formed in sections, one section having a wall overlapping a wall of the other section so as to form a passage between said walls, means to rotate the shell, and peripheral nozzles on one of the shell sections.

11. In a centrifugal amalgamator, the combination of a shell formed in sections, one of said sections having two annular walls and the other section having a wall inserted between the first named walls to form communicating portions of a passage, means to feed ore into the outer portion of the passage, and outwardly directed nozzles connected with the inner portion of the passage.

12. In a centrifugal amalgamator, the combination of a shell rotatively mounted and having an intake at its upper end and an outlet in its periphery near its lower end and having a passage connecting the intake and outlet; means in the passage to retain mercury when the shell rotates, and means to rotate said shell.

13. In a centrifugal amalgamator, the combination of a shell rotatively mounted and having an intake at its upper end and an outlet in its periphery near its lower end and having a passage connecting the intake and outlet, means in the passage to retain mercury when the shell rotates and means to rotate said shell, said outlet being arranged to discharge in a direction opposite to the direction of rotation of the shell.

14. In a centrifugal amalgamator, the combination of a shell rotatively mounted and having a passage extending from near its upper end to near its lower end and thence inward and upward, the outer wall of the passage having a shoulder and extending aslant downward and inward from said shoulder, and means to turn the shell.

15. In a centrifugal amalgamator, the combination of a shell having an annular

passage, a portion of said passage being formed between an outer wall and an intermediate wall, a second portion of said passage being formed between said intermediate wall and a second intermediate wall, a third portion of said passage being formed between said second intermediate wall and an inner wall, and nozzles communicating with said third portion of the passage and discharging peripherally of the shell.

16. In a centrifugal amalgamator, the combination of means forming a helical passage having its axis vertical, a rotatively mounted shell having an annular passage, means to rotate the shell in the direction of the helical progression upward of the helical passage, and a nozzle for the discharge end of the shell passage arranged to discharge in the direction of the helical progression downward of the helical passage.

17. A centrifugal amalgamator comprising a revolving chamber over the outer wall of which mercury is distributed by centrifugal action, said chamber having concentric annular passages communicating at their lower ends, and means to feed ore into the upper side of the outermost passage, said chamber having a discharge passage communicating with the upper side of the other of the annular passages and discharging outwardly away from the chamber in a direction opposite to the direction of rotation of the chamber, the passage from inlet to outlet being restricted and normally closed excepting as to the inlet and outlet and adapted to be normally filled with mercury and pulp while operating.

18. A centrifugal amalgamator comprising a revolving chamber having concentric annular passages communicating at their lower ends, the outer wall of the outermost passage receiving mercury distributed thereupon by centrifugal action, said chamber having ore feed passages communicating with the upper side of the outermost annular passage, and discharge passages communicating with the upper side of the innermost annular passage and adapted to discharge outwardly away from the chamber in a direction opposite to the direction of rotation of the chamber, the passage from inlet to outlet being restricted and normally closed excepting as to the inlet and outlet and adapted to be normally filled with mercury and pulp while operating.

19. A centrifugal amalgamator comprising a revolving chamber over the outer wall of which mercury is adapted to be distributed by centrifugal action, said chamber having annular concentric passages communicating at their lower ends, a discharge nipple on the lower side of the chamber com-

municating with the passages, means to close the discharge nipple, and means to feed ore to the upper side of the outermost annular passage, said chamber having discharge passages communicating with the upper side of the innermost annular passage, and discharging outwardly away from the chamber in a direction opposite to the direction of rotation of the chamber, the passage from inlet to outlet being restricted and normally closed excepting as to the inlet and outlet and adapted to be normally filled with mercury and pulp while operating.

20. In a centrifugal amalgamator, a revolving chamber formed with two annular passages communicating at their lower ends, an ore receiving pan surrounding the chamber, means to feed ore to the upper side of the outermost annular passage, said chamber having a normally closed amalgam discharge opening located at the juncture of said passages and being provided with discharge passages communicating with the upper side of the innermost annular passage and adapted to discharge into the pan in a direction opposite to the direction of rotation of the chamber, the passage from inlet to outlet being restricted and normally closed excepting as to the inlet and outlet and adapted to be normally filled with mercury and pulp while operating.

21. In a centrifugal amalgamator, the combination of a shell having an annular passage, a base member having a tubular extension projecting inside of the shell, a shaft journaled at the upper end of the tubular extension and fastened to the shell and rotatively mounted at the lower portion of the base, means to turn the shaft, a tubular intake member extending into the shell, one portion of the passage being inside of the other portion, and outwardly directed nozzles communicating with the innermost portion of the passage.

22. In a centrifugal amalgamator, the combination of a shell rotatively mounted and having a passage extending from near its upper end to near its lower end and thence inward and upward, the outer wall of the passage having a shoulder and extending aslant downward and inward from said shoulder, outwardly directed nozzles for the last named upwardly extending portion of the passage, and means to turn the shell.

Signed at Los Angeles, California, this 11th day of July, 1917.

SAMUEL G. MUSSER.
